PROTECTOR FOR COVERS OF LOOSE LEAF BINDERS

Frederick C. Bingham, New York, N. Y., assignor to Boorum & Pease Company, Brooklyn, N. Y., a corporation of New York

Application May 28, 1934, Serial No. 728,003

9 Claims. (Cl. 129—24)

This invention relates to devices designed to protect covers, especially flexible covers of loose leaf ring books, from deformation by pressure of the metal rings upon the relatively pliant material of the cover.

It has been the custom in the art for many years to try to meet this problem by providing metal rods or bars at those portions of the cover against which the arcs of the rings strike.

10 However, it has been the practice to build such protectors into the binder in the process of manufacture, as shown for example in the patent to Dawson No. 966,806, granted August 9, 1910, and in the patent to Murphy No. 1,818,999, granted August 18, 1931.

15 The object of the present invention is to provide a practical protector which can be made separately from the binder. Making the protector separable from the binder has the great advantage of economy in cost of manufacture of the binder, as the process of incorporating the protector into the binder during the manufacture thereof is relatively expensive. It also has the further advantage that protectors can be supplied for binders which have already been manufactured without such protectors, and can be inserted easily into the binder by the most inexperienced user thereof. It has the further advantage that it will not interfere in any way 20 with the sheets in the binder and will be effective as a protection to the cover, regardless of the number of sheets in the binder, or of whether there are any sheets in the binder.

25 The invention is illustrated in the accompanying drawings, of which:

Figure 1 is a perspective view of a loose leaf binder showing one of the improved protectors in operative position therein.

Figure 2 is an end section of a binder in closed position showing a pair of the protectors therein.

Figure 3 is a plan view of the protector in broken section, partially broken away to show the construction thereof.

40 Figure 4 is an end view of the protector.

Figure 5 is a plan view of the protector, partially broken away, illustrating its cooperation with the rings of a book.

45 Figure 6 is a view similar to Figure 5, showing a slight modification.

The protector 10 includes a strip 11 having sufficient rigidity to resist deformation by pressure of rings 20 in a well-known type of ring book, such as shown in Figs. 1 and 2.

50 As shown in the drawings, the protector 10

comprises two relatively rigid strips 11 and 12 hinged together at 13, one of the strips being perforated at 14 to receive and fit closely upon the wires comprising rings 20 of the well-known ring book.

5 In Figure 1 is shown such a ring book having the usual rings 20 and flexible cover 21. One of the improved protectors 10 is shown installed on one side of the book. On the other side of the book are shown the usual loose leaves 22 perforated at 23, and the usual flipper or leaf protector 24 perforated at 25 to enable it to flip loosely upon the rings 20.

Figure 2 shows how the strip 11, which is more rigid than the pliant cover 21, prevents 15 the rings 20 from sinking into and deforming the cover at the portion 27, where the arc of the ring would otherwise bear against the cover.

20 As shown particularly in Fig. 5 the perforations 14 in the improved protector are of the same shape as a cross-section of the ring 20 upon which the protector is inserted, and the perforations in the protector are of such size and shape that they fit so closely about the circumference of the wires comprising rings 20 that 25 the protector does not tend to move relatively to the rings of the book unless force is exerted upon it by the operator of the book for the purpose of moving or removing it. In Fig. 5 the perforations 14 in the strip 12 and cross-section 30 of the ring 20 are shown as elliptical.

Figure 6 is similar to Figure 5 except that it shows ring 200 having a circular cross-section and a perforated strip 120 in which the perforation 140 is the same shape, circular, and of substantially the same diameter as the cross-section 35 of the ring 200.

The close fit between the rings 20 and the protector 10 in contrast with the necessarily loose fit between the rings and the leaves 22 is 40 shown in Fig. 1. The leaves 22 are and must be so perforated at 23 as to fit the rings loosely in order to allow the leaves to move freely along the arc of the ring. On the other hand, the strip 12 of the protector 10 is perforated at 14 in 45 such a way that it fits closely upon the wire comprising ring 20, thus eliminating relative movement between the two, in the absence of force supplied by the operator.

45 In using the improved protector the rings 20 50 of the loose leaf book are opened and half rings 19 on one side of the book are threaded into the several perforations 14 in the strip 12 of one of the protectors. The strip 12 is then pushed down to the base of the rings until it 55

rests against the back metal 26 of the book. In this position the hinge 13 will enable the other strip 11 of the protector to interpose itself between the cover 21 and the place 27 where the arc of the ring 20 would otherwise touch and deform the cover 21 of the book.

Due to the close fit between the perforated strip 12 and the rings of the book, the protector will remain at the base of the rings as shown in Figures 1 and 2 so that the strip 11 of the protector will automatically assume the position shown in Figure 2 and be available to protect the cover 21 from the ring 20, regardless of whether or not there are any sheets in the binder.

A simple and economical embodiment of the protector is illustrated in the drawings and is especially clearly shown in Figures 3 and 4.

Strips 11 and 12 are made of any sufficiently rigid material to resist deformation caused by the pressure against them of the rings 20 of the loose leaf book. They may be conveniently made of light weight flexible steel or other suitable material. They are secured together by a hinge 13 which may be of any desired construction. A particularly economical construction is to form the hinge of the same material which forms the covering 15 of the protector. Any strong flexible material, such as imitation leather, or textile fabric, may be used to form the covering 15 and also a flexible fabric hinge at 13. In this form, the somewhat rigid strips 11 and 12 are spaced apart, and the covering 15 is glued or otherwise secured to both sides of said spaced apart strips 11 and 12, forming the hinge 13 between them.

I claim:

1. A device for protecting a cover of a loose leaf binder from rings of said binder, comprising strips hingedly connected, one strip being perforated to receive and fit closely about the circumference of the wire comprising rings of a loose leaf binder, and the other strip being somewhat rigid.
2. A device for protecting a cover of a loose leaf binder from rings of said binder, comprising somewhat rigid strips hinged together, one of said strips being perforated to receive and fit closely about the circumference of the wire comprising rings of a loose leaf book.
3. A loose leaf binder having a cover and rings in combination with a protector to protect said cover from said rings said protector being removable from said rings and comprising strips hingedly connected, one of said strips being perforated and the other strip being somewhat rigid, the distance between perforations being equal to the distance between rings, a cross-section of

of said rings having substantially the same shape and dimensions as the perforations.

4. A loose leaf binder having a cover and rings in combination with a protector to protect said cover from said rings, said protector being removable from said rings and comprising somewhat rigid strips hinged together, one of said strips being perforated, the distance between perforations being equal to the distance between rings, a cross-section of said rings having substantially the same shape and dimensions as the perforations.

5. A loose leaf binder having a cover and operating half rings in combination with a protector readily removable from said rings and comprising somewhat rigid strips hinged together, one of said strips being so perforated that it will receive and fit tightly upon the half rings on one side of the book, and the other strip being of such width that it will lie between the arc of the corresponding half ring and the cover of the binder at the point where the arc and the cover touch.

6. A device for protecting a cover of a loose leaf binder from rings of said binder, comprising somewhat rigid strips spaced apart and flexible material forming a hinge between said strips, one of said strips being perforated to receive and fit closely upon the wire comprising rings of a loose leaf book.

7. A device for protecting a cover of a loose leaf binder from rings of said binder, comprising somewhat rigid strips spaced apart and flexible material covering said strips and forming a hinge between said strips, one of said strips being perforated to receive and fit closely upon the wire comprising rings of a loose leaf book.

8. A loose leaf binder having a cover and rings in combination with a protector to protect said cover from said rings, said protector being removable from said rings and, comprising somewhat rigid strips spaced apart and flexible material forming a hinge between said strips, one of said strips being perforated at intervals equal to the distance between the rings, the cross-section of said rings having substantially the same shape and dimensions as the perforations.

9. A loose leaf binder having a cover and rings in combination with a protector to protect said cover from said rings, said protector being removable from said rings and comprising somewhat rigid strips hinged together, one of said strips being so perforated that it will receive and fit tightly upon the circumference of the wire comprising said rings, and the other strip being of such width that it will lie between the arc of the ring and the cover of the binder at the point where the arc and the cover touch.

FREDERICK C. BINGHAM.
